US0D1086916S

(12) **United States Design Patent** (10) **Patent No.:** **US D1,086,916 S**
(45) **Date of Patent:** **** Aug. 5, 2025**

(54) **DOORBELL**

(71) Applicant: **Google LLC**, Mountain View, CA (US)

(72) Inventors: **Rochus Emanuel Jacob**, San Francisco, CA (US); **Hae rim Jeong**, San Francisco, CA (US); **Adam Duckworth Mittleman**, Redwood City, CA (US); **Shih Ming Tsung**, New Taipei (TW); **Jacobi Colton Grillo**, San Francisco, CA (US); **Jason Evans Goulden**, Los Gatos, CA (US); **Étienne Bérubé**, San Francisco, CA (US); **Minjung Kim**, Sunnyvale, CA (US)

(73) Assignee: **Google LLC**, Mountain View, CA (US)

(**) Term: **15 Years**

(21) Appl. No.: **29/764,257**

(22) Filed: **Dec. 29, 2020**

Related U.S. Application Data

(63) Continuation of application No. 29/694,539, filed on Jun. 11, 2019, now Pat. No. Des. 906,147, which is a continuation of application No. 29/649,733, filed on Jun. 1, 2018, now Pat. No. Des. 879,640, which is a continuation of application No. 29/609,547, filed on Jun. 30, 2017, now Pat. No. Des. 830,872.
